Charles H. Strange, White Plains, N. Y.

Application August 25, 1951, Serial No. 16,439

Term of patent 7 years

(Cl. D74—1)

To all whom it may concern:

Be it known that I, Charles H. Strange, a citizen of the United States, residing at White Plains, county of Westchester, and State of New York, have invented a new, original, and ornamental Design for a Combined Letter Scale, Paper Clips, and Stamp Container, of which the following is a specification, reference being had to the accompanying drawing, forming part thereof, and in which:

Figure 1 is a perspective view of a combined letter scale, paper clips, and stamp container, showing my new design.

I claim:

The ornamental design for a combined letter scale, paper clips, and stamp container, as shown.
CHARLES H. STRANGE.
